RAILWAY TRACK CIRCUIT APPARATUS

Harold G. Witmer, Pittsburgh, Pa., assignor to
The Union Switch & Signal Company, Swiss-
vale, Pa., a corporation of Pennsylvania

Application August 26, 1933, Serial No. 686,952

11 Claims. (Cl. 246—34)

My invention relates to railway track circuit apparatus, and particularly to apparatus in which periodic current is supplied to the traffic rails; and is in the nature of an improvement on the invention covered by an application of Bernard E. O'Hagan, Serial No. 748,675, filed October 17, 1934. A feature of my present invention is the provision of novel and improved apparatus for expediting the release of a track relay when a vehicle enters the section of track with which the relay is associated. Apparatus embodying my invention also provides improved shunting sensitivity of the track circuit. Other features and advantages of my invention will appear as the specification progresses.

I will describe four forms of apparatus embodying my invention, and will then point out the novel features thereof in claims.

In the accompanying drawing, Fig. 1 is a diagrammatic view showing track circuit apparatus embodying my invention. Fig. 2 is a diagrammatic view similar to Fig. 1 but showing a different form of apparatus at the relay end of the track circuit, and Fig. 3 is a view of a modified form of apparatus of Fig. 2, both of which forms also embody my invention. Fig. 4 is a diagrammatic view of another form of apparatus embodying my invention, which form obtains the rectified current for saturating the core of the reactor at the transformer end of the track circuit.

Similar reference characters refer to similar parts in each of the views.

Referring to Fig. 1, the reference characters 1 and 1^a designate the traffic rails of a railway track which are arranged by insulated rail joints 2 to form a track section A—B. The track section A—B is provided with a track circuit, the essential elements of which comprise the traffic rails bonded in the customary manner, a source of current connected across the traffic rails at one end of the section and a track relay energized by energy taken from the traffic rails at the opposite end of the section.

Considering the source of current for the track circuit of the section A—B, the secondary winding 3 of a track transformer T has one terminal connected with the rail 1^a over a resistor 4 and a conductor 5; and its other terminal connected with the rail 1 through the windings 6 and 7 in series of a reactor R to be referred to later and a conductor 8. The primary winding 9 of the transformer T is connected with any convenient source of periodic current such as an alternating current generator not shown in the drawing. It follows that the transformer T constitutes a source of periodic current from which current is constantly supplied to the traffic rails of the section A—B.

60 The reactor R may take different forms and

preferably comprises three magnetizable cores 10, 11 and 12 such, for example, as iron. That is to say, the reactor R is preferably of the type commonly known to the art as a "three-legged" reactor. The windings 6 and 7, which are interposed between the secondary 3 of transformer T and the traffic rail 1, are mounted on the two outer cores 12 and 10, respectively. These windings 6 and 7 are identical and additive as to magnetomotive force and, consequently, substantially no flux created thereby will pass through the center core 11. Mounted on the center core 11 is a winding 13 to which there is supplied unidirectional current in a manner to appear hereinafter. When unidirectional current flows in the winding 13, the direct current flux from the center core 11 returns through the outside cores 10 and 12, and the whole core structure is magnetized. As saturation is approached, the effective permeability of the iron is reduced and the reactance of the windings 6 and 7 is reduced accordingly. It follows that the reactance of the windings 6 and 7 of reactor R can, therefore, be controlled by governing the direct current supplied to the winding 13.

At the relay end of the section A—B, the primary winding 14 of a transformer T¹ has its opposite terminals connected with the traffic rails 1 and 1^a over conductors 15 and 16, respectively, a resistor 17 being interposed in the connection with rail 1^a. The secondary winding 18 of the transformer T¹ is connected across the input terminals of a full-wave rectifier 19, the output terminals of which are connected with the winding of a direct current relay TR, and also across the traffic rails 1 and 1^a. To be explicit, the output terminal 20 of rectifier 19 is connected with one terminal of the winding of the relay TR by a conductor 28, and is connected with the traffic rail 1^a by the conductors 22 and 16. The output terminal 21 of the rectifier 19 is connected with the opposite terminal of the winding of the relay TR by a conductor 29; and with the rail 1 over conductor 23, reactor 24, and conductors 25 and 15. It is clear that the periodic current supplied to the traffic rails at the lefthand end of the section A—B is passed by the transformer T¹ to the rectifier 19, and the track relay TR is energized by a portion of the rectified current, and the remaining portion of the rectified current is supplied to the traffic rails.

Referring again to reactor R, the winding 13 has one terminal connected with the rail 1 over conductors 26 and 8, and its other terminal connected with the rail 1^a over conductors 27 and 5. The winding 13 is so proportioned that it offers a relatively high reactance to the periodic current but a relatively low resistance to direct current. Consequently, the direct current supplied to the traffic rails at the righthand end of the section

A—B flows in the winding 13 and a direct flux is created thereby. It is to be noted that the windings 6 and 7 of reactor R, secondary winding 3 of transformer T and the resistor 4 when taken 5 in series, form a parallel path to the winding 13. The parts are so proportioned, however, that the direct current flowing in this last traced path is relatively small and can be neglected.

It is well known in the art that the ballast resistance of track circuits is constantly changing and may vary over wide limits. This wide variation of the ballast resistance makes it difficult to so adjust a track circuit that proper working value of current is obtained when the ballast is 10 wet, and then not over-energize the track relay when the ballast is dry or frozen. It is also well known that the train shunt resistance, that is, the resistance from one traffic rail to the other through the paths comprising the wheels and 15 axles of the train, varies greatly for different train weights and speeds, and between bright and rusty conditions of the traffic rails. Essential characteristics of a railway track circuit are reliable energizing of the track relay, shunting 20 sensitivity and the shunting period. The shunting sensitivity of a track circuit is the facility with which the track relay is shunted in response to a resistance connected across the traffic rails. That is, if it requires a relatively low resistance 25 path (train shunt) across the traffic rails before the track relay is released the circuit possesses a low shunting sensitivity, and if the track relay is released in response to a relatively high resistance path (train shunt) across the traffic rails 30 the circuit possesses a high shunting sensitivity. The interval lapsing between the time the leading pair of wheels and axle of a train enter the track section and shunt the traffic rails, and the time 35 the track relay releases constitutes the shunting period of the track circuit.

Satisfactory operation of the wayside signal depends upon reliable energization of the track relay when the associated track section is unoccupied, quick release of the track relay in response 40 to a vehicle entering the section, and upon the relay remaining down during the entire period the vehicle occupies any part of the section. It is clear, therefore track circuit apparatus that is capable of normally supplying sufficient energy, 45 that possesses a high shunting sensitivity and that assures a quick release of the relay is essential. Especially is this true when high speed light weight motor cars are to be operated over the track circuit.

I will now describe the operation of the apparatus of Fig. 1 paying particular attention to the manner wherein the apparatus embodying my invention provides improved performance with 50 respect to the characteristics referred to above. The parts are preferably so proportioned that normally the voltage across the terminals of the secondary winding 3 of transformer T will be approximately twice the voltage across the rails 1 and 1^a adjacent the lefthand end of the section 55 A—B. The resulting electromotive force applied to the primary winding 14 of the transformer T¹ will be passed to its secondary winding 13, and hence to the input of the rectifier 19. That portion of the rectified output of rectifier 19 supplied to the winding of the track relay TR will have a magnitude equal to the usual working 60 value of current for track relays of the type here involved. That portion of the rectified output of rectifier 19 supplied to the traffic rails and thence to the winding 13 of reactor R will create

a direct current flux sufficient to substantially saturate the cores of the reactor, and hence the reactance of windings 6 and 7 will normally have a minimum value.

When a train enters the section A—B, the train shunt greatly reduces the voltage applied across the primary winding 14 of the transformer T¹ and the magnitude of the current supplied to the winding of the track relay TR will be reduced in the usual manner. The direct current 10 fed back to the traffic rails will also be greatly reduced and, consequently, the magnetic flux created by the winding 13 of the reactor R will no longer saturate the cores and the reactance of the windings 6 and 7 will be materially increased 15 with the result that the voltage applied across the traffic rails will be greatly reduced. This reduction in the voltage applied to the traffic rails will still further reduce the electromotive force available at the transformer T¹, and hence will act to 20 further reduce the current supplied to the track relay TR, and that relay will be quickly released.

It is clear that with apparatus of the type here disclosed the train shunt resistance which will be effective to bring about a release of the track 25 relay TR will be materially higher than that which is obtained with the usual type of reactor. Furthermore the interval lapsing between the time a train enters the section and the actual release of the track relay will be materially reduced from that which is obtained with customary contemporary equipment. That is to say, the apparatus of Fig. 1 will be effective to normally supply sufficient energy for reliable operation of the track relay under usual variations of 30 ballast resistance, to provide a high shunting sensitivity for the track circuit, and to expedite the release of the track relay in response to a train entering the section.

Referring to Fig. 2, the traffic rails 1 and 1^a 40 are arranged to form a track section A—B the same as in Fig. 1, and the source of periodic current and the reactor R associated therewith are preferably similar to the corresponding devices of Fig. 1. At the righthand end of the 45 section A—B, the primary winding 30 of a transformer T² has its opposite terminals connected across the traffic rails 1 and 1^a, the resistor 17 being inserted in the connection the same as in Fig. 1. A first secondary winding 31 of transformer T² is connected across the input terminals of a rectifier 32, the output terminals of 50 which are connected with the winding of the track relay TR. A second secondary winding 33 of transformer T² is connected across the input 55 terminals of a rectifier 34, the output terminals of which are connected with the traffic rails. To be explicit, the output terminal 35 of rectifier 34 is connected with rail 1^a by a conductor 36; and the output terminal 37 is connected with the rail 1 by conductor 38, reactor 39, and a conductor 40. It follows that a portion of the energy received 60 from the traffic rails by the transformer T² is applied to a first rectifier 32, and the rectified output utilized to energize the track relay TR, and the remaining portion of the energy is applied to the input of a second rectifier 34 and the rectified output thereof supplied back to the traffic rails. The parts of the apparatus of Fig. 2 are so proportioned and adjusted that the track relay 65 TR is supplied normally with the usual working value of current, and the direct current supplied to the traffic rails is sufficient to so energize the winding 13 of reactor R that saturation of the cores of the reactor is obtained.

The operation of the apparatus of Fig. 2 in response to a train entering the section A—B will be essentially the same in all respects to the operation of the apparatus of Fig. 1, and it is thought not necessary to repeat it in detail. It is clear that with proper proportioning of the parts of the apparatus of Fig. 2, the shunting sensitivity of the track circuit will be materially higher and the time required to release the track relay TR will be materially reduced from that obtained in present day practice, and at the same time reliable operation of the track relay will be assured.

Fig. 3 is a modified form of Fig. 2 in which the direct current track relay TR is replaced by an alternating current track relay TR₁. The secondary winding 31 of the transformer T₂ in place of being connected to the input terminals of a rectifier as shown in Fig. 2 is connected directly with the terminals of the winding of the relay TR₁, and hence relay TR₁ is directly supplied with a portion of the alternating current received from the traffic rails. The secondary winding 33 of transformer T₂ is connected with the input terminals of the rectifier 34, and the rectified output supplied to the traffic rails over conductors 36 and 38 the same as in Fig. 2. That is to say, in Fig. 3, a portion of the alternating current obtained from the traffic rails is utilized to energize the track relay, and the remaining portion of the alternating current is converted into unidirectional current and utilized to energize the winding 13 of the reactor R. It is clear that the operation of the apparatus shown in Fig. 3 will be similar to that already described for the apparatus of Figs. 1 and 2.

In Fig. 4, the track section A—B is provided with a track circuit including the track transformer T, the reactor R and the track relay TR, the same as in Fig. 1. At the relay end of the section, the periodic current received from the traffic rails is passed through the transformer T₂ and rectifier 19, and the unidirectional current is then utilized for energizing the track relay TR. The secondary winding 3 of the track transformer T has one terminal connected with the rail 1^a over conductor 5 and its opposite terminal connected with the rail 1 over windings 6 and 7 of reactor R and the conductor 8, the resistor 4 of Fig. 1 being omitted. The primary winding 40 of a transformer T₃ is connected across the conductors 5 and 8 by the conductors 41 and 42, respectively. The secondary winding 43 of the transformer T₃ is connected with the input terminals of a full-wave rectifier 44, the output terminals of which are connected with the winding 13 of reactor R.

The parts are so proportioned that the rectified current supplied through the rectifier 44 to the winding 13 is sufficient to create a direct current magnetic flux sufficient to saturate the cores of the reactor R. The train shunt of any train entering the section A—B will cause the voltage supplied across the primary winding 40 of the transformer T₃ to drop, and hence the current supplied to the winding 13 will be reduced. It follows that the apparatus of Fig. 4 will be effective to provide a high shunting sensitivity for the track circuit and will also provide a quick release for the track relay TR.

Track circuit apparatus such as here disclosed will have a high shunting sensitivity, a relatively quick release of the track relay, and at the same time reliable energization of the track will be assured.

Although I have herein shown and described only four forms of apparatus embodying my invention, it is understood that various changes and modifications may be made therein within the scope of the appended claims without departing from the spirit and scope of my invention.

Having thus described my invention, what I claim is:

1. In combination with a section of railway track, a source of periodic current, means for connecting said source across the traffic rails of the section including a first winding of a reactor having a magnetizable core, a traffic governing relay, means adapted to receive periodic current from the traffic rails for energizing said relay, other means adapted to receive periodic current from the traffic rails of the section including an asymmetric unit for converting the periodic current into unidirectional current; and means connected with the output of said asymmetric unit, including the rails of said section and a second winding of said reactor, for governing the flux in the core of the reactor.

2. In combination with a section of railway track, a source of periodic current, means for connecting said source across the traffic rails of the section including a first winding of a reactor having a magnetizable core, a traffic governing relay, means adapted to receive periodic current from the traffic rails for energizing said relay, other means adapted to receive periodic current from the traffic rails of the section including an asymmetric unit for converting the periodic current into unidirectional current; and a circuit including the output of said asymmetric unit, a rail of said section and a second winding of the reactor; for varying the permeability of the core of said reactor to control the periodic current supplied to the traffic rails.

3. In combination with a section of railway track, a source of periodic current, means for connecting said source across the traffic rails of the section including a first winding of a reactor having a magnetizable core and a pair of conductors, a traffic governing relay, means adapted to receive periodic current from the traffic rails for energizing said relay, other means adapted to receive periodic current directly from said pair of conductors independently of the traffic rails of the section and including an asymmetric unit for converting the periodic current into unidirectional current, and means connected with the output of said asymmetric unit including a second winding of the reactor for governing the flux in the core of the reactor whereby the reactance of said first winding is controlled in accordance with the presence or absence of a train in said section.

4. In combination with a section of railway track, a source of periodic current, means for connecting said source across the traffic rails of the section including a first winding of a reactor having a magnetizable core, a second winding mounted on the core of said reactor, circuit means including a source of direct current supplied over the rails of said section for energizing said second winding to create a steady magnetic flux for determining the reactance of said first winding, means governed by traffic conditions of said section for controlling said circuit means whereby the voltage of the periodic current supplied across the traffic rails is varied in accordance with the presence or absence of a train in said section, and receiving means connected across

the traffic rails of the section including an electroresponsive device effectively influenced by the periodic current.

5. In combination with a section of railway track, a source of periodic current, a reactor having a center and two outside magnetizable cores, means for connecting said source across the traffic rails of the section including a first and a second winding mounted on the outside cores 10 respectively and arranged in such a manner that magnetomotive forces created thereby are additive, a third winding mounted on the center core, circuit means including a source of direct current supplied over the rails of said section for 15 energizing said third winding to create a steady magnetic flux for determining the reactance of said first and second windings, traffic controlled means responsive to a train entering said section for controlling said circuit means whereby 20 the voltage of the periodic current supplied to the traffic rails is varied in accordance with the presence or absence of a train in said section, and receiving means connected across the traffic rails of the section including an electroresponsive device 25 effectively influenced by the periodic current.

6. In combination with a section of railway track, a source of periodic current, a reactor at one location of the section having a center and two outside iron cores, means for connecting said source across the traffic rails including a first and a second winding mounted on the outside cores respectively and arranged in such a manner that magnetomotive forces created thereby are additive, a third winding mounted on the 30 center core of the reactor, a first means at the reactor location of the section receiving periodic current from said source and including the input terminals of a full-wave rectifier also at the reactor location, means including the output 35 terminals of said rectifier for supplying unidirectional current to said third winding for controlling the permeability of the cores of said reactor to govern the periodic current supplied to said traffic rails, and a second means receiving periodic current from the traffic rails including a 40 traffic governing electroresponsive device.

7. In combination with a section of a railway track, a source of periodic current, a reactor having a center and two outside magnetizable cores, 50 means for connecting said source across the traffic rails at one end of the section including a first and a second winding mounted on the outside cores respectively and arranged in such a manner that magnetomotive forces created thereby are additive, a third winding mounted on said center core, circuit means including a source of direct current supplied over the traffic rails of the section for energizing said third winding to create a steady magnetic flux for determining the 55 reactance of said first and second windings and thereby control the periodic current, receiving means connected across the traffic rails at the other end of the section to receive the periodic current, a traffic governing electroresponsive device controlled by said receiving means, and traffic controlled means responsive to a train entering said section for controlling said circuit means.

8. In combination with a section of railway 70 track, a source of periodic current, a reactor having an auxiliary and two main magnetizable cores, means for connecting said source across the traffic rails at one point including a first and a

second winding mounted on the two main cores respectively, a first means receiving the periodic current from the traffic rails at another point including the input terminals of a rectifier, means including the output terminals of said rectifier for supplying the rectified current to the traffic rails, means connected across the traffic rails at said one point including a winding mounted on said auxiliary core and adapted to receive said rectified current to create a magnetic flux in the 10 cores of the reactor for determining the reactance of said first and second windings and thereby control the periodic current, and a second means receiving current from the traffic rails at said other point including an electroresponsive device 15 effectively governed by the periodic current.

9. In combination with a pair of conductors, a source of alternating current, means for connecting said source across said conductors at one point including a first winding of a reactor having a 20 magnetizable core, receiving means connected across the conductors at another point effectively influenced by said alternating current, operating means controlled by said receiving means, other means controlled by said receiving means including an asymmetric unit and connected across the conductors at said other point for supplying unidirectional current to said conductors, and means connected across the conductors at said one point including a second winding of said reactor effectively influenced by the unidirectional current for varying the permeability of the core of said reactor to control the alternating current supplied to the conductors.

10. In combination with a section of railway 35 track, a source of periodic current, means for connecting said source across the traffic rails at one end of the section including a first winding of a reactor having a magnetizable core, receiving means connected across the traffic rails at the 40 other end of the section adapted to receive said periodic current, means governed by said receiving means including an asymmetric unit and connected across the traffic rails at said other end of the section for supplying a portion of the 45 periodic current back to the traffic rails as unidirectional current, and means connected across the traffic rails at said one end of the section including a second winding of said reactor and adapted to receive the unidirectional current for varying 50 the permeability of the core of said reactor to control the periodic current supplied to the traffic rails.

11. In combination with a section of railway track, a source of periodic current, a reactor having an auxiliary and two main magnetizable cores, 55 means for connecting said source across the traffic rails at one point including a first and a second winding mounted on the two main cores respectively, a third winding mounted on the auxiliary core, a transformer having its primary winding connected across the traffic rails at said one point and its secondary winding connected with the input terminals of a rectifier, means for connecting the output terminals of the rectifier 60 with said third winding to create a magnetic flux in the cores of the reactor for determining the reactance of said first and second windings, and means connected across the traffic rails at another point of the section including an electroresponsive means effectively controlled by the periodic current.

HAROLD G. WITMER.
